UNITED STATES PATENT OFFICE.

JACOB CAPRON, OF NEW YORK, N. Y.

IMPROVEMENT IN ELECTRO-MAGNETIC ANNUNCIATORS.

Specification forming part of Letters Patent No. 117,979, dated August 15, 1871.

To all whom it may concern:

Be it known that I, JACOB CAPRON, of New York, in the county of New York and State of New York, have invented a new and useful Improvement in Hotel-Annunciators; and I do hereby declare that the following is a full and exact description of the same, reference being had to the accompanying drawing and to the letters of reference marked thereon.

This invention relates to that class of annunciators for hotels, &c., which is operated by electricity; and consists in certain details of construction, which will be fully described hereinafter.

In the drawing, Figure 1, sheet 1, represents a rear elevation of my improved annunciator; Fig. 2, sheet 2, a side elevation; Figs. 3, 4, and 5, sheet 2, views of parts detached; Fig. 6, sheet 3, a top view; and Fig. 7, a front elevation.

To enable others skilled in the art to make and use my invention, I will now proceed to describe fully its construction and manner of operation.

This annunciator is provided with a face-plate for displaying the numbers designating the different rooms of the house, these numbers being covered ordinarily by a pivoted plate hung upon one side of its pivot, which is caused to fall or swing downward for the purpose of exposing the number, by suitable mechanism operated by wires connecting with the different rooms. The operation of the mechanism which exposes the number also causes a gong to sound, by which means the attention of the clerk is obtained. Suitable mechanism is also provided for the purpose of restoring the covering-plates to their former positions after the call has been answered. The numbered display-plate, the covering-plates, and tumblers or dogs by which the latter are operated, and also the slide and crank for restoring the covering-plates to place again, are each and all of them fully described in my patent of December 27, 1870, and they need not, therefore, be particularly referred to here. My invention in this instance particularly relates to the mechanism by means of which the dogs or tumblers of the covering-plates are permitted to fall, and also to the mechanism for operating the gong.

The mechanism for operating the dogs of the covering-plates is as follows: A metallic frame, B, is caused to project at right angles from the supporting-board of the tumblers from a point at a suitable distance above each tumbler, upon

which is located an electro-magnet, the armature of which is connected to the short arm of the elbow-lever C. The long arm of the lever C extends over the tumbler, and is provided with a slight projection, c, Fig. 5, against which the long finger a of the tumbler A rests when the covering-plate is in position. The electro-magnet is connected by suitable wires with any proper battery, and with the room which the number designates. At a suitable point in the room is located a circuit-breaker consisting of a disk, D, sheet 2, provided with a knob, d, having a sliding shank through a suitable socket, as shown. The reverse side of this disk is provided with a stud having an insulated screw, d', to which one of the wires is connected, as shown. The other wire is directly attached to the disk in any suitable manner.

From this description it will be observed that the current is ordinarily broken, as there is no connection made between the insulated screw d' and the disk. When desired, however, a connection may be easily made by pressing in the knob, in which case its shank will touch the screw-pin d', and thus complete the circuit. When it is desired, therefore, to notify the clerk at the office that something is wanted in the room, the occupant thereof presses in the knob d, and thus completing the circuit causes the electro-magnet to act and attract its armature attached to the elbow-lever, by which means its short arm is depressed and its long arm correspondingly raised. This elevation of the long arm of the lever deprives the dog or tumbler of the support against which it rested, and consequently the overbalanced covering-plate is permitted to fall.

The arrangement of wires is as follows: One main wire, m, is provided, to which one of all the pairs of wires leading from the rooms is connected. The other wire m' of the pairs is led directly to a spring-plate, n, the free end of which ordinarily rests against the side of pin n', which is in its turn directly connected to one end of the electro-magnet. The main wire m is first conducted to the electro-magnet connected with the gong, into which a branch wire leads, and then to the other end of the electro-magnet. It will thus be perceived that ordinarily the circuit is complete through the electro-magnet operating the tumblers of the face-plates, with the exception of the break in the room, but that this cir-

cuit does not run through the gong. As soon, however, as the tumbler is permitted to fall, a change takes place, as follows: The long finger of the tumbler falls upon the free end of the spring-bar *n* below, and depresses it so that its contact with the pin *n'* is broken. By this means the circuit through the electro-magnet operating the tumblers is broken; but by means of the tumblers *a* a connection is made with the metallic frame upon which the magnet rests, from which a wire leads to a plate, *E*, and from thence through intermediate connections to the electro-magnet operating the gong. As the main wire *m* has a branch also leading to this magnet, the latter is caused to act, and consequently its armature *F* is drawn down, to which is attached the gong-hammer.

It is desirable at times to have the gong sound an alarm, and for this purpose a peculiar construction and arrangement of parts is provided. The plate *E* is constructed with a socket in which moves a sliding shaft operated by a knob upon the outside of the case. The inner end of the shaft is provided with a disk which rests either against a standard, *G* or *G'*, according to its position in the socket; when drawn backward it rests against the standard *G*, and when thrust forward, against the standard *G'*. In the former position, connection is made by means of the standard *G* with the base-plate of the magnet upon which rests its metallic frame from which a wire leads into the coil, and a single blow is struck upon the gong. When in the latter position, however, the direction of the current is changed. The wire from standard *G'* leads to an insulated bar, *H*, which projects over the spring-armature of the magnet beneath. This bar is provided with a pin, *h*, which projects downward and rests ordinarily in contact with a curved arm attached to the spring-armature. The latter is insulated from the bar *H*, but rests upon the metallic frame of the magnet. It therefore follows that connection is made with the magnet through the spring-armature. It follows further, therefore, that as soon as the armature is depressed by the operation of the magnet the current

is broken, and consequently the magnet must cease to operate. The spring-armature is thus permitted to rise again to position, by which means connection is again made with the spring *h*. This operation is repeated, and the gong caused to sound so long as the current is kept complete from the room in which the call is made. For convenience, the sliding shaft is provided with a spring and suitable means for holding it when the latter is compressed.

This machine is simple in all its parts and not liable to get out of order.

Having thus fully described my invention, what I claim as new, and desire to secure by Letters Patent, is—

1. The combination of a lever having the armature of an electro-magnet attached thereto with the dog or tumbler *A*, substantially as described.

2. The combination of a swinging or dropping-dog connected directly or indirectly to the gong with a spring-bar or arm connected with one of the room-wires, the dog and bar being relatively so arranged that the falling of the former forms a new connection with the latter, substantially as described.

3. A dog or tumbler adapted to fall and break the circuit which has operated the electro-magnet that caused its fall, and further adapted, also, to form a new circuit with the gong.

4. The metallic frame supporting the insulated electro-magnet which operates the dog, and connected to the gong by means substantially as described.

5. The plate *E* with its sliding shaft, constructed as described.

6. The combination of the plate *E* and its shaft with the standard *G* or *G'*, the parts being relatively arranged as described.

7. The insulated bar *H*, in combination with the spring armature and a wire adapted to conduct a current through the bar *H*, as described.

This specification signed and witnessed this 13th day of April, 1871.
